(57) **CLAIM**

The ornamental design for legs of a printer stand, as shown and described.

DESCRIPTION

FIG. 1 is a perspective view of a printer stand having legs and on which a printer is attached.

FIG. 2 is an upside-down perspective view of the printer stand having legs of FIG. 1.

FIG. 3 is a perspective view of the legs of the printer stand of FIG. 1.

FIG. 4 is a front view of the legs of the printer stand of FIG. 1. The back view and the right and left side views of the legs are identical to the front view of FIG. 4.

FIG. 5 is a top view of the legs of the printer stand of FIG. 1; and,

FIG. 6 is a bottom view of the legs of the printer stand of FIG. 1.

Any portions shown in broken lines in the figure are for illustrative purposes only and form no part of the claimed design.

1 Claim, 6 Drawing Sheets
